UNITED STATES PATENT OFFICE

161,194

COMBINED COMB STAND AND TRAY

Peter Morroni, Leominster, Mass.

Application December 17, 1949, Serial No. 6,681

Term of patent 14 years

(Cl. D86—10)

To all whom it may concern:

Be it known that Peter Morroni, a citizen of the United States, residing at Leominster, in the county of Worcester, State of Massachusetts, has invented a new, original, and ornamental Design for Combined Comb Stand and Tray, of which the following is a specification, reference being had to the accompanying drawing, forming part thereof.

Fig. 1 is a plan view;
Fig. 2 is a view in front elevation;
Fig. 3 is a section on line 3—3 of Fig. 1; and
Fig. 4 is a view in end elevation of a combined comb stand and tray showing my new design.

I claim:

The ornamental design for a combined comb stand and tray, as shown.

PETER MORRONI.
